UNITED STATES PATENT OFFICE.

WILHELM HEIDECKER, OF NEW HAMPTON, IOWA.

BRACE FOR THRESHING-MACHINES.

SPECIFICATION forming part of Letters Patent No. 645,420, dated March 13, 1900.

Application filed August 21, 1899. Serial No. 727,949. (No model.)

To all whom it may concern:

Be it known that I, WILHELM HEIDECKER, a citizen of the United States, residing at New Hampton, in the county of Chickasaw and State of Iowa, have invented new and useful Improvements in Jacks for Bracing and Steadyng Threshing-Machines, of which the following is a specification.

My invention relates to jacks for threshing and other analogous machines whereby they may be braced and steadied and prevented from moving back and forth while in operation.

The object of the invention is to provide an improved jack for the above purpose which can be readily applied to a threshing-machine without loss of time and which will effectually brace and steady the machine.

The invention consists in the novel construction and combination of parts hereinafter fully described and claimed.

In the accompanying drawings, Figure 1 is a longitudinal sectional view of a portion of a threshing-machine, showing my improved jack applied thereto. Fig. 2 is a side elevation of the jack removed.

In the said drawings the reference-numeral 1 designates the front axle, 2 one of the wheels, and 3 the bolster, of a threshing-machine of any ordinary or suitable construction.

The numeral 4 designates a base-board of any suitable material and size, and 5 two oppositely-inclined bars, the lower ends of which rest on said board, while the upper ends are adapted to engage with the bolster of the machine. Passing through one of said bars, near the lower end thereof, is a screw-rod 6, the inner end of which is formed with a hook 7. Engaging with said rod outside the bar

is a screw-threaded bur 8, provided with a 40 crank 9, by turning which the rod is forced outwardly. Connected with the other bar is a chain 10, with one of the links of which the hook 7 is adapted to engage.

The manner of using the device is as follows: The board 4 is placed on the ground between the front wheels of the thresher, with the upper ends of the bars engaging with the bolster of the latter. By now turning the crank 9 the screw-rod will be moved outwardly, causing the lower ends of the bars to be forced toward each other, so that the upper ends will tightly clamp the bolster. This will cause the machine to be braced and steadied, preventing to-and-fro movement of the same while in operation, which is very injurious to the machine. The device can be readily and quickly applied and obviates the use of blocks or checks usually employed for the purpose.

Having thus fully described my invention, what I claim is—

The herein-described jack and brace consisting of the inclined bars, disconnected at their upper and lower ends, a screw-rod passing through one of said bars and having a hook at its inner end, the bur and crank, and the chain connected with the other bar and with the hook on the rod, substantially as described.

In testimony whereof I have hereunto set my hand in presence of two subscribing witnesses.

WILHELM HEIDECKER.
